AUTOMATIC REPERTORY DIALING MACHINE

Richard Kobler, West Orange, N.J., and Carl L. Otto,
New York, N.Y., assignors to McGraw-Edison Company,
Elgin, Ill., a corporation of Delaware

Filed Jan. 23, 1963, Ser. No. 73,284

Term of patent 14 years

(Cl. D26—5)

FIG. 1

FIG. 2

FIG. 3

FIGURE 1 is a perspective view of an automatic repertory dialing machine showing our new design, the sliding cover for the push buttons being pushed into storing position;

FIGURE 2 is a side elevational view with the cover in open position; and

FIGURE 3 is a plan view to larger scale of this machine as shown in FIGURE 2.

The essential features of our design reside in the portions shown in solid lines. The broken line showing of the name and number list is for illustrative purposes only.

We claim:

The ornamental design for an automatic repertory dialing machine, substantially as shown and described.
